UNITED STATES PATENT OFFICE

106,272

DESIGN FOR A WRIST FLASHLIGHT CASING

Norwood Anderson, Chester, N. Y.

Application February 6, 1937, Serial No. 67,481

Term of patent 14 years

To all whom it may concern:

Be it known that I, Norwood Anderson, a citizen of the United States, residing at Chester, in the county of Orange and State of New York, have invented a new, original, and ornamental Design for a Wrist Flashlight Casing, of which the following is a specification, reference being had to the accompanying drawing, forming part thereof.

In the drawing:

Figure I is a rear perspective view of a wrist flashlight casing with the strap fragmentarily illustrated showing my new design; and

Fig. II is a front elevational view thereof.

I claim:

The ornamental design for a wrist flashlight casing as shown and described.

NORWOOD ANDERSON.
